CLAIM

The ornamental design for a metal detector, as shown and described.

DESCRIPTION

FIG. 1 is a front, top perspective view of a metal detector, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view of the metal detector, shown in an alternative position;

FIG. 10 is a rear, bottom perspective view thereof;

FIG. 11 is an enlarged view of detail "11" identified in FIG. 1; and,

FIG. 12 is an enlarged view of detail "12" identified in FIG. 1.

The dashed lines in the figures illustrate portions of the metal detector that form no part of the claimed design. The dash dot dash lines in FIGS. 1, 11 and 12 are for the purpose of illustrating the enlarged view indicators and form no part of the claimed design.
